ATTORNEY.

UNITED STATES PATENT OFFICE.

HENRY J. BUBENHEIM, OF PITTSBURGH, PENNSYLVANIA.

GAS-BURNER.

1,119,569.

Specification of Letters Patent.

Patented Dec. 1, 1914.

Application filed February 12, 1914. Serial No. 818,208.

To all whom it may concern:

Be it known that I, HENRY J. BUBENHEIM, a citizen of the United States, residing at Pittsburgh, in the county of Allegheny and State of Pennsylvania, have invented a certain new and useful Improvement in Gas-Burners, of which the following is a specification.

This invention has for its primary object 10 the provision of a new and practical form of burner, wherein economy in the consumption of gas and an extremely high temperature is prevalent by mixing the fuel gas with vapor arising from a liquid introduced 15 into the burner. To the normal heat units contained in the fuel gas are added the gases given off by the liquid, usually water, in the form of vapor or steam, which combined gases, being thoroughly united, tends 20 to produce an intense heat at the point of ignition. It is obvious that the desired result will be accomplished by mixing the fuel gas and moist vapor gases inside the burner, below the point of ignition. This 25 construction is clearly disclosed in the accompanying drawings, which involves one specifically illustrated embodiment of my invention, but I reserve the right to make necessary alterations and amendments there- 30 to which will be within the scope of the appended claims.

Referring then to said drawings Figure 1 is a plan view of my preferred form of burner having the upper apertured cover 35 removed: Fig. 2 is an elevation in cross section of the fully assembled burner showing necessary supply pipes.

The main body portion of the burner is a hollow U-shaped casting, here shown as 40 being circular in form, but which can be of any desired configuration, and is designated by the numeral 1, the upper extremity of the vertically disposed side walls being provided with flanges 2, which support a corre- 45 spondingly flanged, removable and slotted cap or cover 3, the same being preferably arc-shaped as shown. Intermediate of these two members 1 and 3 is a suitable wire mesh

or screen 4, all of which foregoing elements being held together by ordinary securing 50 bolts 5.

The fuel gas is supplied to the burner by a pipe 6, which is here shown as being connected to a centrally disposed four-way union 7, from which radiate distributing 55 pipes 8, the outer ends of which connect to elbows 9. Joined to these elbows are vertically disposed pipes 10 which enter through the bottom of the hollow body 1 and extend upward to a point above the 60 horizontal plane of said screen member 4, directly underneath the apertured cap element 3.

Inside the hollow body 1, preferably near the bottom portion, as shown, is a fluid supply pipe 11, the same preferably being in 65 two sections connected by a nipple 12 to which is joined a common supply pipe 13. The outer free ends of these two sections of pipe are capped, and on the under side are 70 provided with a plurality of escapement apertures 14.

Closely packed in the hollow body 1 around the fluid supply pipes 11 and gas supply means 10, occupying practically all 75 the space below the screen 4, is an absorbent material 15, preferably of a non-combustible nature, such as mineral wool or similar substance, which is intended to retain or act in the capacity of a wick, for the fluid supplied thereto.

Water is first supplied to the burner in the manner shown and described, thereby saturating the filling 15. Upon the gas being ignited heat thus generated throughout 85 the burner converts the water into steam or vapor which, rising, mixes with the gas above the screen 4, and this combination of gas and vapor produces a more intense heat at the exterior point of ignition than could 90 be obtained by using the gas singly.

What I claim as my invention is:

1. In a gas burner a suitable hollow body portion; a perforated cap secured to said body; a mesh intermediate of the body and 95 cap; an absorbent filling inside the hollow

body; means for supplying moisture to said filling; and means for supplying gas above the mesh.

2. In a gas burner a suitable hollow body portion; an apertured spacing cover for said body; a screen intermediate of the body and cover; an absorbent non-combustible filling inside the hollow body below the screen; means for supplying moisture

to said filling; and means for supplying gas to the space above the screen.

In testimony whereof, I affix my signature in the presence of two witnesses.

HENRY J. BUBENHEIM.

Witnesses:

M. S. THOMPSON,
H. W. STEVENSON,
